UNITED STATES PATENT OFFICE.

TALBOT C. DEXTER, OF PEARL RIVER, NEW YORK.

PAPER-FEEDING MACHINE.

No. 880,198.

Specification of Letters Patent.

Patented Feb. 25, 1908.

Application filed March 22, 1907. Serial No. 363,796.

To all whom it may concern:

Be it known that I, TALBOT C. DEXTER, a citizen of the United States, and a resident of Pearl River, in the county of Rockland and State of New York, have invented certain new and useful Improvements in Paper-Feeding Machines, of which the following is a specification.

My present invention relates to improvements in paper feeding machines of the sheet-combing type, in which the pile of sheets is acted upon by combing-feeding devices which comb or feather out the top sheets of the pile to gradually separate the successive sheets near the top, so they may be drawn from the pile periodically and fed to any machine arranged to operate upon the individual sheets.

My present invention relates to improvements in the sheet actuated mechanism for controlling the operation of the sheet feeding mechanisms to automatically register the successive sheets in the machine as they are fed forward upon the pile.

My present improvements are of the pneumatic type in which the control of the sheet moving mechanisms is effected through the medium of air suction devices acting beneath the path of the sheets so as to entirely relieve the sheets from the objectionable engagement of trip fingers or similar devices which are commonly arranged above the path of the sheets, and are objectionable because of their interference with the free movement of the sheets from the pile.

My present improvements will be best understood as applied to a paper feeding machine of the type illustrated in Letters Patent No. 829,854, granted to me August 28th, 1906, and in my applications Serial No. 329,898, filed August 9th, 1906, and Serial No. 360,000, filed March 1st, 1907. I have illustrated my present improvements as applied to this type of feeding machine, but it will, of course, be understood that I do not intend to limit the scope of the claims upon my present invention to this particular type of feeding machine, but wish to cover the said invention in a broad sense without reference to the particular structure of the feeding machine to which it is applied.

As in my former machines above referred to, my present improvements control the action of the sheet moving mechanisms by actuating suitable devices for raising the

sheet moving mechanisms out of engagement with the sheets. This is accomplished through the medium of a two part clutch mechanism and a controlling pawl, as in my former machines, by arranging the controlling pawl under the influence of pneumatic devices which are controlled by the sheets. In the preferred arrangement of the improved mechanism, I provide two suction tubes or nozzles beneath the plane of travel of the sheets upon opposite sides of the central longitudinal line of the machine, and connect these suction nozzles through suitable pipes with small cylinders in which operate pistons connected directly with the controlling pawls of the clutch mechanisms. These pistons are normally held by means of delicate springs in position to maintain the controlling pawls out of engagement with the ratchets of the clutch mechanisms during the time that the sheet moving mechanisms are acting. The moment the sheet reaches registered position above the suction nozzles, the suction through the pipes leading from the nozzles to the cylinders is cut off by the sheet and the suction action causes the pistons to move in their cylinders to throw the pawls into engagement with the ratchets of the clutch mechanisms. The suction cylinders are connected through suitable pipes with a rotary air pump, (or pumps) and the suction action through the pipes is further controlled by means of valves actuated by the movements of the sheet-moving mechanisms into and out of active positions.

The mechanism of my present application is distinguishable from the machine of my above-named application Serial No. 360,000, in that it includes the slip clutch mechanisms of the machine shown in my above-named Patent No. 829,854, and provides for the operation of the controlling pawls of such clutch mechanisms by the sheet controlled suction devices; whereas in the machine of my said application Serial No. 360,000, such clutch mechanisms are omitted, and the sheet controlled suction devices are directly connected with the restraining means of the comber elevating mechanisms.

My present invention also includes means actuated by the suction devices for preventing the operation of the drop roller delivery mechanism in the absence of a properly registered sheet; also certain features of general

construction by which the main features are carried out.

In order that my invention may be fully understood, I will first describe the same with reference to the accompanying drawings, and afterwards point out the novelty more particularly in the annexed claims.

In said drawings Figure 1 is a vertical longitudinal sectional view of the main parts of a paper feeding machine embodying my invention. Fig. 2 is a front elevation, partly broken away, of the mechanism shown in Fig. 1. Fig. 3 is a detail vertical longitudinal sectional elevation of parts of the same mechanism, showing more particularly the pneumatic control of the comber elevating and lowering mechanism of my improved machine. Figs. 4, 5 and 6 are detail views of the sheet controlling suction nozzle, and the front guide which co-operates therewith. Fig. 7 is a detail elevation of the sheet controlled clutch mechanism which actuates the comber elevating mechanism. Figs. 8, 9, 10, 11 and 12 are detail views of the main controlling valve of the suction pipe. Fig. 13 is a sectional view illustrating the relief valve of the suction pipe. Fig. 14 is a detail longitudinal sectional view showing the pneumatic cylinder and piston for controlling the position of the clutch pawl and comber controlling latch. Fig. 15 is a view similar to Fig. 7 showing the application of a simple device for disengaging the controlling pawl from the ratchet of the clutch mechanism. Fig. 16 is a side elevation of the same mechanism, and Fig. 17 is a transverse sectional view looking from the opposite side of the same mechanism.

Sheet combing feeding machines of the type to which my present invention relates are provided with two sets of sheet combing devices arranged to operate at opposite sides of the machine. In the accompanying drawings, I have shown only one half of the machine including only one of these sheet combing devices, but it will be understood that two combing devices of the same construction are employed, each being independently controlled by a sheet actuated pneumatic mechanism.

The frame-work of my improved machine may be of any suitable construction to properly support the working parts hereinafter referred to. In the drawings, 1, 1, represented the vertical side frames. These side frames are suitably braced to make them rigid by means of stay rods 2, 3, and other frame parts not shown, and within the frame is provided a suitable table or support for carrying a pile of sheets, indicated by the reference letter P. At the front of the pile of sheets, I provide a series of vertical guide rods or strips (not shown) for confining the pile.

5 is a constantly driven shaft bearing the

lower feed rollers 6, said shaft 5 being braced at intervals by suitable bearing brackets, (not shown).

8 are drop rollers journaled in the bifurcated rock arms 9, mounted upon the transverse rock shaft 10. The rock shaft 10 extends transversely of the machine, above the constantly running lower shaft 5, and is suitably braced between its ends by two or more bracket arms 11 rigidly secured to the auxiliary longitudinal frame pieces 12. The rock shaft 10 is operated by the usual mechanism, whereby the series of drop rollers 8 are periodically raised and lowered for performing their function.

21 and 22 are respectively the under feed roller and drop-roller of a folding machine to which the feeder is to pass the sheets.

The main cam shaft 20 extends transversely of the machine and is suitably journaled in the main side frames 1 and the auxiliary longitudinal frame pieces 12. This shaft 20 is provided with a driving pulley 25, as shown, or it may be driven in any other suitable manner, said shaft being the shaft from which all other parts of the machine are driven.

The cam shaft 20 carries a large gear 26, which meshes with a smaller gear 27, secured to a larger gear 28, journaled upon a stud 29, projecting from the side frame of the machine. The gear 28 meshes with and drives a smaller gear 30 journaled upon a stud 31, projecting from the side frame of the machine, and this gear 30 in turn drives a smaller gear (not shown) keyed to the projecting end of the comber driving shaft 35 hereinafter referred to, and a smaller gear 33 keyed to the projecting end of the constantly rotating feed shaft 5 above referred to.

40 is one of a pair of combing wheels. Each of these combing wheels is freely journaled at 41 upon a rock arm 42, which is freely journaled upon a sleeve 50 which is in turn journaled upon the shaft 35. This shaft 35 (driven as stated) has keyed to it a gear 45 which meshes with a gear 46 secured to the combing wheel 40, by which the combing wheel is constantly rotated.

Projecting from one face of the comber supporting rock arm 42 is an integral lug 43 in which is mounted an adjustable tappet screw 44. Secured upon the sleeve 50 to one side of the rock arm 42 is a rock arm 51 which is provided with a finger 52, which projects beneath the tappet screw 44 just referred to, and by its engagement therewith lifts the combing wheel away from the pile. By adjusting the screw 44, the limits of rise and fall of the combing wheel can be fixed.

The rock arm 51 is moved in one direction for lifting the combing wheel by a spring mechanism which is released by the sheet actuated tripping device hereinafter explained. The rock arm 51 is moved in the

opposite direction to allow the combing wheel to move by gravity into engagement with the pile of sheets by the action of a cam as will now be explained.

5 Sleeve 50 has at its end, adjacent to the rock arm 51, another rock arm 55 to which is pivotally connected a pitman 56, formed with a yoke-shaped upper end, which straddles the shaft 20. The shaft 20 carries a 10 peripheral cam 58, which engages an anti-friction roller journaled upon the pitman 56, whereby the rock arm 55, sleeve 50, and finger 52 are moved once in each revolution of the shaft 20 to reset the tripping mechanism 15 (hereinafter described) and allow the combing wheel to rest upon the pile.

The rock arm 51 projects forwardly from the sleeve 50 and has pivotally connected to its forward end a yoke-shaped latching bar 60 extending vertically and formed at its 20 upper end with a contracted guide-bar portion 60^a which rides in a socket formed in a bracket 62 extending laterally from one of the central auxiliary frames 12. Pivoted 25 at 63^a in the upper end of the loop of the yoke-shaped latching bar 60, is a toggle link 63 which is pivotally connected at its lower bifurcated end, by pivot pin 64^a, with the upper bifurcated end of the lower toggle link 64. The toggle link 64 is pivotally 30 mounted at its lower end upon a pivot pin 64^b between ears 65^a extending from an angular bracket arm 65 which is secured to one of the frame pieces 12. The ears 65^a project with- 35 in the loop of latching bar 60, so as to support the lower end of the lower toggle link therein and maintain the thrust of the toggle in line with bar 60. The purpose of the latching bar 60 and toggle links 63, 64, is to 40 retain the rock arm 51 and the spring device connected thereto, (presently to be referred to), in position to allow the operation of the combing wheel. 66 is an antifriction roller journaled upon pin 64^a.

45 I will now proceed to describe the spring device and will afterwards explain the mechanism for releasing the latching mechanism under the control of the sheets fed from the pile.

50 A rod 70 is pivoted at 71 to the rock arm 51 and projects therefrom vertically through a guide pin 72 projecting from the bracket 62. Surrounding the rod 70 and confined between a collar 70^a above the rock arm 51 55 and guide pin 72 is an expansion spring 75, which tends to throw down the arm 51 and move up the finger 52 for raising the combing away from the pile of sheets. This spring tendency is normally restrained by the toggle 60 links 63, 64 and the latching bar 60.

Turning now to the sheet actuated pneumatic tripping mechanism for controlling the operation of the combing devices, I will first refer to the clutch mechanism which trips 65 the spring controlled latching mechanism

under the action of the sheet actuated tripper, then the means for operating the mechanism and finally the structure and operation of the sheet controlled suction devices.

Each of the auxiliary frame pieces 12 carries a vertical bracket plate 81, upon which are mounted the sectional clutch shaft, and the operating rack, hereinafter referred to.

Bracket arms 90 are secured to and project rearwardly from the plate 81 in position to 70 support the sectional clutch shaft consisting of members 91 and 92, illustrated in detail in Figs. 7 15 and 17 of the drawings. The clutch shaft members 91 and 92 are of hollow or tubular form, as shown in Fig. 17, each 80 one being suitably journaled in one of the arms of the bracket 90. The shaft member 91, in addition to being movable about its axis is capable of moving longitudinally in its bearing 90. This member 91 has mounted upon it or formed integral with it, a gear wheel 93 driven by a rack (hereinafter referred to) to cause it to oscillate, or by some rotary gear, when it is desired to cause it to rotate continuously in one direction. This 90 clutch mechanism will operate with either an oscillatory or a rotary movement. Clutch member 91 also carries one member 94 of a cam faced slip clutch formed in its working 95 face with a plurality of radial cam faced recesses 94^a. The other tubular shaft member 92 has mounted upon one end or formed integral therewith a ratchet wheel 95, and upon its opposite or inner end the other member 96 of the slip clutch, formed upon its working 100 face with a plurality of radial cam faced ribs or lugs 96^a. Secured within the hollow sectional clutch shaft is a spring device 103 constructed and arranged as clearly illustrated and described in my above named Patent 105 No. 829,854, but not shown in detail herein, which spring device tends to hold the two parts of the clutch 94—96 in engaged position, so that the ratchet wheel 95 will be oscillated or rotated from the gear 93 through 110 the hollow shaft sections 91—92.

The bracket bearings 90 support the sectional clutch shaft 91—92 transversely of the machine and approximately in line with the knuckle joint connecting the toggle 115 links 63—64, the toggle links extending across the line of the hollow sectional shaft, so that any longitudinal movement of the shaft section 91 toward the toggle levers, will engage roller 66 and force the knuckle of 120 the toggle levers outwardly, thereby breaking the toggle latch and allowing the spring actuated rod 70 to raise the combing wheel from the pile of sheets. This movement of the shaft section 91 is effected by arresting 125 the rotation of the shaft section 92 which is accomplished through the medium of the sheet actuated pneumatic or suction tripping devices hereinafter referred to.

The vertical bracket plate 81 carries at its 130

lower end a rearwardly projecting dovetail track bar 110, upon which is mounted a horizontally reciprocating carriage 111, having secured to its upper edge a rack bar 112, 5 which is in constant mesh with the gear wheel 93 upon shaft member 91. The carriage 111 is constantly reciprocated forwardly and backwardly by means of a rock arm 115 depending from a rock shaft 116, and 10 pivoted at its lower end to a link 117, which link has pivotal connection 118 with a lug upon the carriage 111.

The rock shaft 116 is suitably journaled in the machine frame, and extends from side 15 to side of the machine. This rock shaft 116 carries at its outer end a depending rock arm 121 pivoted at its lower end 122 to a link 123 which is actuated by a cam or crank mechanism 130 on shaft 20. The sectional 20 clutch shaft 91, 92, may, if preferred, be rotated constantly in one direction by suitable gearing meshing with gear 93.

Each sectional clutch mechanism 91, 92, is under the control of a pneumatic sheet-acted 25 tripping device including a pawl 140 journaled at 141 in position to engage one of the ratchet wheels 95 as shown in Fig. 3 of the drawings. Each pawl 140 is connected through a pitman 145 with a hollow piston 30 146 having spring 146^a operating freely in a suction cylinder 147, mounted upon the bracket arm 148. The cylinder 147 has open communication at 149 with an elbow pipe 150 connected with a vertical air pipe 35 151 leading from the valve casing 152. Extending laterally from the vertical air pipe 151 is a branch air pipe 153 leading to one side of the machine, and then downwardly beneath the plane of feed, and then toward 40 the center of the machine where its end is formed into a flattened and broadened suction nozzle 155 closed at its end and formed with a plurality of small orifices 155^a in its upper face, as shown in Fig. 4. This flattened perforated end of the air tube is extended for a short distance horizontally in the plane of feed so as to present the series of orifices 155^a in a line at right angles to the line of feed, which line is the line of registry 45 of sheets preparatory to their delivery from the machine.

The valve casing 152, shown in detail in Figs. 8, 10 and 11, has a free passage-way through it vertically, and an air exhaust 55 port 152^a through one side wall. Rotatably mounted in the valve casing 152 is a transverse three-way valve plug 160, of hollow formation. This valve plug 160 is provided with the three ports 160^a, 160^b and 160^c. 60 Secured to the outer end of the valve plug is a rock arm 161, to which is pivotally connected a rod or pitman 162 pivoted at its lower end to an arm 163 secured to and projecting from the journal end of rock arm 42 65 upon which the combing wheel 40 is mounted.

By this arrangement it will be observed that the elevation and lowering of the combing wheel will operate the three-way valve for opening up communication through the valve casing when the combing wheel is in 70 operative engagement with the pile, and for closing off this direct communication from the valve casing when the combing wheel is elevated. This operation will be hereinafter 75 more fully explained.

The valve casing 152 communicates through a short pipe section 165 with a three-way coupling 166. Leading from one end of the coupling 166 is a pipe 167, which is coupled to an air pump of any suitable construction, not shown. The purpose of the air pump is to constantly exhaust air through the system of pipe above described, the action of the air in the operation of the machine being controlled by the suction nozzles 155 and the main controlling valves 152. Leading from the other end of coupling 166 is a pipe 168 provided in its ends with a suction relief valve 169 of ordinary construction. This relief valve, as shown in Fig. 13 of the 80 drawings, consists of a conical valve stem seated in a conically recessed plug and having a spring to normally hold the valve closed, and suitable guides in which the valve stem operates. There is nothing novel claimed in 85 the specific structure of the relief valve.

It will be understood that the suction mechanism just described is arranged at one side of the machine. The pipe 167 may communicate with the same suction mechanism of the other side of the machine so that one air pump will serve to exhaust the air through both systems of pipes, but I have found it preferable to employ two independent air systems with a separate air pump for 100 each system, in which case each system will consist essentially of all of the above described elements.

As pointed out in my above named application Serial No. 360,000, the suction nozzles 155 arranged in the line of registry of the sheets being fed from the pile is ordinarily a sufficient provision for the proper positioning of the sheets preparatory to the operation of the drop roller mechanism. In some 110 cases, however, it is desirable to provide, in addition to the suction tubes, some form of front gages to further insure the proper registry of the sheets. I have illustrated a form of front guides which may be used for 115 this purpose, but I would have it understood that I do not limit the use of the sheet controlled suction mechanism to machines having front guides, since the suction mechanism may be used without such additional 120 registering means.

175 are ordinary front guides or fingers mounted upon rock shafts 176 and formed with bifurcated downturned gage flanges 175^a, through which project the spring fin- 130

gers 177 adjustably secured to the front guides. These front guides 175 are arranged to position the sheets above the suction nozzles 155, the spring fingers 177 serving to exert a light downward pressure upon the sheets resting above the suction nozzles. Projecting upwardly from each rock shaft 176 is a rock arm 180 connected through a link or pitman 181 with a rock arm 182 secured to the drop roller rock shaft 10. By reason of this connection it will be observed that when the drop rollers 8 are lowered into contact with the under-feed rollers 6, the front gages 175 will be elevated out of the path of the sheets, and vice versa.

Projecting upwardly from one of the drop roller supporting rock arms 9, is a controlling rod 185, which passes through a guide strap or bracket 186, and is provided beneath the guide bracket with a stop collar 187. Pivoted at 188 upon a part of one of the auxiliary frames 12 is a latch arm 189 which is adapted to engage beneath the collar 187 to hold the controlling arm 185 and the drop rollers with which it connects in elevated position. This latch arm 189 is connected through a link 190 with the controlling pawl 140, which is actuated by the suction mechanism above described. This arrangement is such that when the controlling pawl 140 is disengaged from the ratchet wheel 95, the latch arm 189 will engage the collar 187 and hold the drop rollers out of operation; whereas the movement of the pawl 140 into engagement with the ratchet to cause the arrest of operation of the combing wheel (which happens only when the sheet has been fed forward into registered position), will withdraw the latch arm 189 from the path of collar 187 and allow the drop rollers to operate under the control of their cam in the usual manner. The front gages are controlled in the same manner by reason of the described connection with the drop roller mechanism.

When the rotary sectional clutch mechanisms are driven constantly in one direction it sometimes happens that the ratchet wheel 95 will bind so tightly upon the controlling pawl 140, when the pawl is thrown into engagement for the purpose above explained, that some difficulty is experienced in disengaging these parts when the mechanisms are reset.

In Figs. 15, 16 and 17 of the drawings I have shown a simple mechanism for positively disengaging the controlling pawl from the ratchet wheel 95 immediately after the combing wheel has been elevated from the pile of sheets. In these Figs. 15, 16 and 17 of the drawings, the section clutch mechanism is the same as above described, the same being driven by suitable gearing with the gear wheel 93. The ratchet wheel 95 on the section of the shaft which is momenta-

rily stopped is in this form of mechanism engaged by a controlling pawl 140' of slightly different shape for accomplishing the same result as the controlling pawl above referred to. The pawl is connected as above described by the rod or pitman 145 with the piston of the suction cylinder.

Extending parallel with the sectional clutch shaft 91, 92, is a short rock shaft 210 journaled in a suitable bearing in the machine frame. Secured to one end of this rock shaft 210 is a rock arm 211 carrying at its end a laterally projecting pin 212 which rests directly beneath the controlling pawl 140'. Secured to the opposite end of the short rock shaft 210 is a rock arm 213 which projects downwardly toward the sectional clutch shaft to one side of the outer face of the gear wheel 93. A sufficient space is allowed between rock arm 213 and the face of the gear wheel 93 to permit the normal free rotation of a series of detents or lugs 215 which project laterally from the face of the gear 93. The rock arm 213 is preferably formed of the shape shown. From this construction it will be observed that when the controlling pawl 140' engages the ratchet wheel 95 and arrests the shaft section 91, the continued rotation of the shaft section 91 will cause the slip clutch to force said shaft section and the gear 93 to the left as shown in Fig. 15, which action will throw the detents or lugs 215 into the path of the rock arm 213, so that one of said lugs coming into engagement with rock arm 213 will rock the shaft 210 and cause the rock arm 211 to positively disengage the controlling pawl 140' from the ratchet wheel 95. This means for disengaging the pawl from the ratchet wheel may be also employed in connection with the other form of the clutch mechanism in which the sectional clutch shaft is oscillated forward and backward, but the disengaging mechanism is not so necessary in said other form of the clutch.

Extending longitudinally of the machine, at each side is a rock shaft 200 journaled in bracket arms 201 extending down from the auxiliary frame pieces 12. At the forward end of each of these rock shafts is a rock arm 202 carrying at its upper end an antifriction roller 203, which operates in engagement with a face cam 204, keyed to the cam shaft 20. Each of the rock shafts 200 carries a horizontal rock arm which is adjustable longitudinally of the machine, and carries a weighted tail gripper 205 of the same construction as fully set forth in my above named patent.

The following brief explanation will make clear the operation of my improved machine: It being understood that a machine embodying my improvements is provided with two sets of sheet combing mechanisms, each independently controlled by a sheet actuated

suction device as described, the machine is started in operation with the combing wheels resting upon the top of the pile of sheets, the combing wheels being driven through the 5 gears as above explained. In this normal operative position of the machine, the spring elevating mechanisms for the combers are held out of action by the restraining means above described. In this position 10 of the parts the main controlling valves 152—160 are open (that is in the position shown in Fig. 11), so that the air pump or pumps will continually exhaust air through the system of piping, the air being supplied 15 through the suction nozzles 155. The two combing wheels will continue to operate until the forward edge of the top sheet in front of one of the combing wheels is moved forward sufficiently to close the ports or openings 20 155^a of one of the suction nozzles 155. At the same time, or immediately thereafter, the edge of the sheet adjacent to the closed suction nozzle will contact with the front 25 guide, which co-operates with said nozzle, the suction of the nozzle upon the sheet also assisting in the registering operation. When the openings in one of the nozzles has been closed, the supply of air from this source is cut off with the result that a partial vacuum 30 will be formed in the suction cylinder 147 with which the closed nozzle is in communication. The suction in this cylinder acts upon the piston 146 to move the controlling pawl 140 (or 140') into engagement with the 35 controlling ratchet 95 to actuate the sectional clutch shaft mechanism for tripping the releasing mechanism and allowing the spring device to elevate the combing wheel behind the closed suction nozzle. This action is 40 immediately followed by the same operation at the other side of the machine with the result that both combing wheels will be raised away from the pile and the top sheet will be moved forward in registered 45 position. At the same time that the pawl 140 is moved into engagement with the ratchet wheel 95, the controlling latch 189 is withdrawn from engagement with the collar or shoulder 187 of the controlling arm 185 to 50 release the drop roller mechanism and the front gages to the action of the main controlling cam. As each combing wheel is raised from the pile, the valve 152—160 is also automatically shifted to shut off communication 55 between the air pump and the suction nozzles and to automatically break the suction in the nozzles by opening up communication with the outside air through valve parts 160^c, 160^b and 152^a, the controlling 60 valve in this position being as shown in Fig. 10 of the drawings. As each valve is actuated for closing off the communication with the pump, the pump is supplied with the necessary air to allow it to operate by the automatic action 65 of the valve 169.

As each combing wheel is raised from the pile and the suction in the suction nozzle is broken as explained, the spring 146^a will move the piston 146 outwardly for disengaging pawl 140 from the ratchet. If the 70 ratchet binds the pawl too tightly, the mechanism illustrated in Figs. 15, 16 and 17 of the drawings may be employed for disengaging the pawl.

The drop roller mechanisms feed the registered sheet from the pile in the ordinary manner, the lowering of the drop rollers causing the elevation of the front gages by reason of their above described connections. After the top sheet has completely left the 80 pile the cams 58 will forcibly rock the sleeves 50 to permit the combing wheels to again fall into operative engagement with the top of the pile of sheets, and at the same time reset the spring devices and restraining 85 mechanisms and shift the main controlling valves to their normal positions of operation.

Having thus described my invention what I claim as new and desire to secure by Letters Patent is:

1. The combination, in a paper feeding machine, of a sheet moving instrument, means controlling the operation of the sheet moving instrument, a ratchet wheel included 95 in said controlling means, a pawl adapted to engage said ratchet wheel, and sheet controlled suction means for actuating said pawl.

2. The combination, in a paper feeding 100 machine, of a sheet moving instrument, means controlling the operation of the sheet moving instrument, a ratchet wheel included in said controlling means, a pawl adapted to engage said ratchet wheel, a 105 spring normally holding the pawl disengaged from the ratchet wheel, and sheet controlled suction means for moving said pawl into engagement with the ratchet wheel.

3. The combination, in a paper feeding 110 machine, of a sheet moving instrument, means for raising and lowering the sheet moving instrument, including a ratchet wheel, a pawl adapted to engage said ratchet wheel, and sheet controlled suction means 115 for actuating said pawl.

4. The combination, in a paper feeding machine, of a sheet moving instrument, means controlling the operation of the sheet moving instrument, a longitudinally movable throw-out shaft included in said controlling means, and sheet controlled suction means adapted to effect the longitudinal movement of said shaft.

5. The combination, in a paper feeding 125 machine, of a sheet moving instrument adapted to be moved into and out of engagement with a sheet, means adapted to elevate the sheet moving instrument, means for restraining the action of the elevating means,

a longitudinally movable throw-out shaft adapted to release said restraining means, and sheet controlled pneumatic mechanism for effecting the longitudinal movement of the throw-out shaft.

6. The combination, in a paper feeding machine, of a sheet moving instrument adapted to be moved into and out of engagement with a sheet, means adapted to elevate said sheet moving instrument, means for restraining the action of the elevating means, a longitudinally movable throw-out shaft adapted to release said restraining means, sheet controlled suction mechanism for effecting the longitudinal movement of the throw-out shaft, and an automatically operated valve for relieving the suction of said mechanism.

7. The combination, in a paper feeding machine, of a sheet moving instrument adapted to be moved into and out of engagement with a sheet, a spring device adapted to elevate the sheet moving instrument, means for restraining the action of the spring device, a longitudinally movable throw-out shaft adapted to release said restraining means, and sheet controlled pneumatic mechanism for effecting the longitudinal movement of the throw-out shaft.

8. The combination, in a paper feeding machine, of a sheet moving instrument adapted to be moved into and out of engagement with a sheet, means adapted to elevate the sheet moving instrument, means for restraining the action of the elevating means, a longitudinally movable throw-out shaft adapted to release said restraining means, sheet controlled pneumatic mechanism for effecting the longitudinal movement of the throw-out shaft, and cam mechanism adapted to reset the restraining means.

9. The combination, in a paper feeding machine, of a sheet moving instrument adapted to be moved into and out of engagement with a sheet, means adapted to elevate said sheet moving instrument, means for restraining the action of the elevating means, a longitudinally movable throw-out shaft adapted to release said restraining means, sheet controlled suction mechanism for effecting the longitudinal movement of the throw-out shaft, a relief valve for relieving the suction of the suction mechanism, cam mechanism adapted to move said instrument into engagement with the sheet and reset the restraining means, and means for operating said valve actuated by the movements of said instrument into and out of operation.

10. The combination, in a paper feeding machine, of a sheet moving instrument adapted to be moved into and out of engagement with a sheet, a spring device adapted to elevate the sheet moving instrument, means for restraining the action of the spring device, means including a ratchet and a pawl

adapted to release said restraining means, and sheet controlled suction mechanism for actuating said pawl.

11. The combination of a sheet moving instrument, means for elevating the sheet moving instrument, a shaft section movable longitudinally and about its axis, means actuated by the longitudinal movement of said shaft section for releasing the elevating means, a second shaft section movable about its axis, slip-clutch members secured upon the respective shaft sections, means acting on one of said shaft sections for moving both shaft sections about their axis, and sheet controlled pneumatic means acting upon the other shaft section to arrest its movement about its axis.

12. The combination of a sheet moving instrument, means for controlling the operation of the sheet moving instrument, a shaft section movable longitudinally and about its axis, means actuated by the longitudinal movement of said shaft section for actuating the controlling means, a second shaft section movable about its axis, slip-clutch members secured upon the respective shaft sections, means acting on one of said shaft sections for moving both shaft sections about their axis, a ratchet wheel upon the other shaft section, a pawl adapted to engage said ratchet to arrest the movement of said other shaft section about its axis, and sheet controlled suction means for actuating said pawl.

13. The combination of a sheet moving instrument, a spring device for elevating said sheet moving instrument, cam mechanism for lowering said instrument, a shaft section movable longitudinally and about its axis, means actuated by the longitudinal movement of said shaft section for releasing the spring device, a second shaft section movable about its axis, slip-clutch members secured upon the respective shaft sections, means acting on one of said shaft sections for moving both shaft sections about their axis, and sheet controlled suction means acting upon the other shaft section to arrest its movement about its axis.

14. The combination of a sheet moving instrument, means for elevating the sheet moving instrument, a shaft section movable longitudinally and about its axis, means actuated by the longitudinal movement of said shaft section for releasing the elevating means, a second shaft section movable about its axis, slip-clutch members secured upon the respective shaft sections, a pawl and ratchet mechanism adapted to arrest the movement about its axis of one of said shaft sections, sheet actuated suction means for moving said pawl into engagement with said ratchet, and a spring normally holding said pawl disengaged from the ratchet.

15. The combination of a sheet moving instrument, means for elevating the sheet mov-

ing instrument, including a pawl and ratchet mechanism, drop roller mechanism, a latch restraining the drop roller mechanism, and a sheet actuated pneumatic means controlling said pawl and said latch.

16. The combination of a sheet moving instrument, means for elevating the sheet moving instrument, means for releasing the elevating means, including a pawl and ratchet
10 mechanism, drop roller delivery mechanism, front gages movable into and out of gaging position, means connecting the drop roller mechanism and front gages, a latching device adapted to restrain the movement of the
15 drop roller mechanism and gages.

17. The combination of a sheet moving instrument, means for elevating the sheet moving instrument, a shaft section movable longitudinally and about its axis, means 20 actuated by the longitudinal movement of said shaft sections for releasing the elevating means, a second shaft section movable about its axis, slip-clutch members secured upon the respective shaft sections, a toothed member 25 moved by one of said shaft sections, a pawl adapted to engage said toothed member to arrest the movement of said shaft section about its axis, and sheet actuated suction means controlling said pawl.

30 18. The combination of a sheet moving instrument, means for elevating the sheet moving instrument, a clutch mechanism controlling the elevating means, a toothed member carried by said clutch mechanism,
35 a pawl adapted to engage said toothed member to cause the operation of the clutch mechanism, and sheet actuated suction means controlling said pawl, and including a suction relief nozzle supported in the path of
40 sheets.

19. The combination of a sheet moving instrument, means controlling the operation of the sheet moving instrument, including a ratchet wheel, a pawl adapted to engage 45 said ratchet wheel, a suction cylinder having suitable communication with air exhausting means, a suction nozzle supported in the path of the sheets and communicating with said suction cylinder, and a piston operating 50 in said cylinder and suitably connected with said pawl.

20. The combination of a sheet moving instrument, means controlling the operation of the sheet moving instrument, including a 55 ratchet wheel and a pawl adapted to engage said ratchet wheel, a suction cylinder having suitable communication with air exhausting means, a suction relief nozzle supported in the path of the sheets and communicating 60 with said suction cylinder, a piston operating in said cylinder and suitably connected with said pawl, and an automatic suction controlling valve.

21. The combination of a sheet moving instrument, means controlling the operation

of the sheet moving instrument including a ratchet wheel, a pawl adapted to engage said ratchet wheel, a suction cylinder having suitable communication with air exhausting means, a suction nozzle supported in the path of the sheets and communicating with said suction cylinder, drop roller delivery mechanism, a latch controlling the operation of the drop roller mechanism, and a piston operating in said cylinder and suitably connected with said pawl and with said latch. 70 75

22. The combination of a sheet moving instrument, means controlling the operation of the sheet moving instrument, a ratchet and a pawl included in the controlling means, sheet controlled suction means for actuating said pawl and having communication with a suitable air pump, a valve in said communication between the suction means and air pump, and means actuated by the movement of the instrument into and out of operation for operating said valve. 80 85

23. The combination of a sheet moving instrument, means for controlling the movement of the sheet moving instrument into and out of operation, a longitudinally movable throw-out shaft included in said controlling means, sheet controlled suction means adapted to effect the longitudinal movement of said shaft, a suitable air pump in communication with the suction means, a valve in said communication between the suction means and air pump, and means actuated by the movement of the instrument into and out of operation for operating said valve.

24. The combination of a sheet moving instrument, means for raising and lowering the sheet moving instrument, controlling means including a ratchet and a pawl, sheet 105 controlled suction means for actuating said pawl, said suction means having communication with a suitable air pump, a valve in said communication between the suction means and air pump, and means actuated by the 110 elevation and lowering of the instrument for operating said valve.

25. The combination of a sheet moving instrument, means controlling the operation of the sheet moving instrument including a ratchet wheel, a pawl adapted to engage said ratchet wheel, sheet controlled means for actuating said pawl, drop roller delivery mechanism, a controlling arm connected with the drop rollers, a controlling latch actuated by the sheet controlled means and adapted to engage said controlling arm. 115 120

26. The combination of a sheet moving instrument, means controlling the operation of the sheet moving instrument including a ratchet wheel, a pawl adapted to engage said ratchet wheel, sheet controlled suction means for actuating said pawl, drop roller delivery mechanism, a controlling arm connected with the drop rollers, and a latch connected 125. 130

with said pawl and adapted to engage said controlling arm.

27. The combination of a sheet moving instrument, sheet controlled means controlling the operation of the sheet moving instrument, drop roller delivery mechanism, a controlling arm connected with the drop rollers, a shoulder on said controlling arm, and a latch actuated by the sheet controlled means and adapted to engage the shoulder on said controlling arm.

28. The combination of a sheet moving instrument, means controlling the operation of the sheet moving instrument including a ratchet wheel, a pawl adapted to engage said ratchet wheel, sheet controlled means for actuating said pawl, drop roller delivery mechanism, a controlling arm connected with the drop rollers, a latch connected with said pawl and adapted to engage said controlling arm, suitable front guides, and connections between said front guides and the drop roller mechanism.

29. The combination of a sheet moving instrument, sheet controlled suction means controlling the operation of the sheet moving instrument and including a suction nozzle arranged in the path of sheets, suitable front guides in operative relation to the sheets, and connections between said front guides and the controlling means.

30. The combination of a sheet moving instrument, sheet controlled suction means controlling the operation of the sheet moving instrument, said suction means including a suction nozzle arranged in the path of sheets drop roller delivery mechanism, suitable front guides in operative relation to the sheets, and connections between said front guides, the drop roller mechanism and said controlling means.

31. The combination of a sheet moving instrument, suitable drop roller mechanism, suitable front guides, rock arms connected respectively with the drop rollers and front guides for causing them to operate alternately, and sheet controlled suction means

controlling the operation of the sheet moving instrument and the connected drop rollers and front guides.

50

32. The combination of a sheet moving instrument, means controlling the operation of the sheet moving instrument, including a ratchet wheel, a pawl adapted to engage said ratchet wheel, sheet controlled means for actuating said pawl, and means actuated by the engagement of the pawl with the ratchet wheel for disengaging the pawl from the ratchet wheel.

33. The combination of a sheet moving instrument, means controlling the operation of the sheet moving instrument, including a ratchet wheel, a pawl adapted to engage said ratchet wheel, sheet controlled means for actuating said pawl, a rotatable detent, a rock shaft carrying two rock arms, one of which is adapted to be engaged by said detent, and the other of which is adapted to engage said pawl for disengaging the pawl from the ratchet wheel, and means actuated by the arrest of the ratchet wheel by the pawl for moving the detent into position to engage said rock arm.

34. The combination of a sheet moving instrument, means controlling the operation of the sheet moving instrument, including the ratchet wheel, a pawl adapted to engage said ratchet wheel, sheet controlled means for actuating said pawl, a longitudinally movable rotary throw-out shaft, a plurality of detents mounted upon said shaft, means actuated by the engagement of said pawl with said ratchet for causing the longitudinal movement of said shaft, a rock shaft carrying a rock arm adapted to engage said pawl, and a second rock-arm mounted upon said rock shaft with which said detents are adapted to engage when the throw-out shaft is moved longitudinally.
